US00D914733S

(12) **United States Design Patent** (10) **Patent No.:** **US D914,733 S**
Fischbach (45) **Date of Patent:** **** Mar. 30, 2021**

(54) **DISPLAY SCREEN OR PORTION THEREOF WITH GRAPHICAL USER INTERFACE**

(71) Applicant: **Siemens Schweiz AG**, Zürich (CH)

(72) Inventor: **André Fischbach**, Steinhausen (CH)

(73) Assignee: **SIEMENS SCHWEIZ AG**, Zurich (CH)

(**) Term: **15 Years**

(21) Appl. No.: **29/737,002**

(22) Filed: **Jun. 4, 2020**

Related U.S. Application Data

(62) Division of application No. 35/504,879, filed on Nov. 9, 2017 (U.S. filing date under 35 U.S.C. 384), and having an international filing date of Nov. 9, 2017, now Pat. No. Des. 887,437.

CLAIM

The ornamental design for a display screen or portion thereof with graphical user interface, as shown and described.

DESCRIPTION

The FIGURE is a display screen or portion thereof with graphical user interface.

The broken lines showing an electronic device are included to illustrate environmental structure; the broken lines showing portions of the graphical user interface are included to illustrate portions of the article; all broken lines form no part of the claimed design.

1 Claim, 1 Drawing Sheet
